UNITED STATES PATENT OFFICE.

LEANDER M. PROWSE, OF SILOAM SPRINGS, ARKANSAS.

BED-SPRING.

SPECIFICATION forming part of Letters Patent No. 315,546, dated April 14, 1885.

Application filed May 5, 1884. (No model.)

To all whom it may concern:

Be it known that I, LEANDER M. PROWSE, a citizen of the United States of America, residing at Siloam Springs, in the county of Benton and State of Arkansas, have invented 5 certain new and useful Improvements in Bed-Springs, of which the following is a specification, reference being had therein to the accompanying drawings.

10 My invention relates to bed-bottoms or portable spring-bed frames.

The construction and arrangement of the device will be hereinafter more fully set forth in the specification and pointed out in the accompanying drawings, in which—

15 Figure 1 is a plan view of one section or portion of the bed-frame with the springs attached, and Fig. 2 is a detail view of the interwoven tension-springs.

20 Referring more particularly to the drawings, A A' represent the coiled springs, secured to the frame-pieces B B'. These coiled or spiral springs are united by the lateral spring portions *a*, thus practically making these spiral springs one integral or common spring.

25 Any strain taken up by one of the spirals A A' is immediately communicated to the other through the intervention of the uniting part *a*. These spirals are further united to each 30 other and to the opposite ones on the frame by the spirally-coiled springs C C'.

35 It will be observed that the springs C C' have their ends interwoven over a portion of each of the spirals A A', the central part at *c* being interwoven again with each other, the ends of the frame having also the springs E, similar to C C', stretched between and interwoven with the spirals A.

40 What is shown in plan view Fig. 1 represents a portion or section of the bed-frame, and it is of course well understood that there may be any suitable number of said sections. In each case the springs C C' are interwoven and extended across from spiral to spiral, as shown.

45 The object sought for and the advantages secured by this form of construction are as follows: The spirals A A' and their connections act to take up a direct vertical strain

upon them; but in order that this weight shall be evenly distributed over the springs these 50 spirals are united by the springs C C', which are interwoven at their central point, or at the intersection of the diagonals drawn from the opposite corners of the rectangle formed by the frame-pieces P. Hence any tendency 55 to undue weight on one portion of the springs more than the other is immediately taken up and neutralized by the springs C C', which are joined to the springs A A' at a point about centrally of said springs and the frame-pieces 60 B, and are continuous throughout the length of the frame. If this were not the case, the spirals A A' and their connections would be gradually compressed out of form and become 65 bent and useless for the purpose required. Heretofore, in order to get a good bearing for the mattress and prevent the springs from becoming bent, it has been necessary to use a large number of springs joined to each other 70 in various ways. I accomplish this object in 75 a cheap and effectual way by the use of few springs joined as described.

Having thus described my invention, what I claim is—

80 In a bed-bottom, the combination, with the frame, of the spiral springs A A', made integral by means of the joining spring portions *a*, and the intermediate curved springs, C C', extending in an unbroken line across the bed-bottom, and interwoven at their central point 85 between the spirals A A', and interlacing with them at a point central of the spirals and frame-pieces B, whereby the vertical and tensile strains are uniformly taken up and distributed, substantially in the manner and for the purpose set forth.

In testimony whereof I affix my signature, in presence of two witnesses, this 26th day of December, A. D. 1883.

his
LEANDER X M. PROWSE.
mark.
